UNITED STATES PATENT OFFICE.

GEORGE D. WILKINSON AND AUGUSTUS F. HARTER, OF OAK PARK, ILLINOIS, ASSIGNORS TO CRIBBEN & SEXTON COMPANY, OF CHICAGO, ILLINOIS, A CORPORATION OF ILLINOIS.

FLUE CONNECTION.

Application filed June 12, 1924. Serial No. 719,535.

To all whom it may concern:

Be it known that we, GEORGE D. WILKINSON and AUGUSTUS F. HARTER, citizens of the United States, residing at Oak Park, in the 5 county of Cook and State of Illinois, have invented a new and useful Improvement in Flue Connections, of which the following is a specification.

This invention relates particularly to a 10 flue-device for use in connection with ranges or stoves. The improved device is particularly useful in connection with gas-ranges, or combination gas-ranges and stoves.

The primary object of the invention is to 15 provide a flue connection which will enable the outlet flue of a stove or range to be connected with a wall-flue, regardless of whether the flue outlet of the stove or range registers with the wall-flue after the stove 20 has been set in the desired position.

The invention is illustrated in its preferred embodiment in the accompanying drawing, in which—

Figure 1 represents a rear perspective 25 view of the improved flue connection, embodying the invention; Fig. 2 represents a broken vertical sectional view showing the improved device forming a connection between the outlet flue of a gas-range and a 30 wall-flue, the section being taken as indicated at line 2—2 of Fig. 1; Fig. 3, a horizontal sectional view taken as indicated at line 3—3 of Fig. 1; Fig. 4, a front perspective view of the flue-connection; and Fig. 5 is a perspective view 35 of one of the shiftable plates employed.

In the construction illustrated, A represents a gas-range; B, a wall provided with a flue, or chimney-passage, B'; and C, the 40 improved flue-connection.

The device C preferably comprises a flat rectangular hollow body 1 whose front wall 2 is provided with an opening, or passage 2^a, and whose rear wall 3 is provided with 45 a rectangular opening 3^a; a vertically adjustable plate 4 disposed back of the wall 3 and provided with a rectangular passage 4^a; and a horizontally movable plate or slide 5 disposed back of the plate 4 and 50 equipped with a central perforation 5^a at the margin of which is a collar 5^b.

The hollow body 1 is in the form of a flat shallow box which is disposed in 55 a vertical plane. This box comprises a flanged front section 2^b; and a

flanged rear section 3^b whose bottom affords the wall 3. The flanges of the sections are telescopically related, and the sections may be secured together in any suitable manner. The rear section 3^b is provided at its lateral 60 corners with guide flanges 6 which form, with the wall 3, guides for the lateral edges of the vertically adjustable plate 4.

The plate 4 is provided with horizontal flanges 4^b which form guides for the plate 65 5. The plate 5 is considerably longer than the box 1, and is provided at its ends with flanges 5^c.

From the description given, it will be understood that the plate 4 may be adjusted 70 vertically, and that the plate 5 may be adjusted horizontally, to bring the collar, or pipe-connection, 5^b to any desired point, for example, into registration with a pipe 75 extending into an opening 8 of the flue B'.

As shown in Fig. 4, the front wall 2 of the box 1 may be provided with perforations 9 for enabling the device to be fastened to the rear wall of a stove or range, as by means of stove bolts 9^a. In this position, the 80 passage 2^a registers with an outlet passage, or flue, 10 of the stove or range. Thus, it will be seen that the smoke or vapors may pass from the oven, or other source, and may enter the interior of the box 1, and may pass from the box 1 through the outlet passage to the wall-flue B'.

From the description given, it will be understood that the outlet flue of the gas-range, or stove, may be readily connected 90 with the wall-flue, even though said flues are not in registry. Ordinarily, the gas-range is placed only a few inches from the wall; and the improved device provides a ready means of connection between the flue 95 of the range and the wall-flue, allowing a considerable amount of latitude in locating the range in the kitchen. It will be noted that the desired result is obtained by the

possibility of shifting the collar 5^b, which connects with one of the flues, in two directions, thus enabling the collar 5^b to be brought into registration with such flue, while the interior space 11 of the device is in communication through the passage 2^a with the other (stove) flue. If desired, the flue-connection may be reversed, i. e. either side may be towards the stove.

The foregoing detailed description has been given for clearness of understanding 110

- only, and no unnecessary limitations should be understood therefrom, but the appended claims should be construed as broadly as permissible, in view of the prior art.
5. What we regard as new, and desire to secure by Letters Patent, is:
1. A device of the character set forth comprising a hollow body provided at one side with a flue passage communicating with the 10 interior of said body, a slide movably mounted on the other side of said body and provided with a passage, and a slide movably mounted on said first-named slide and provided with a passage.
  15. 2. A device of the character set forth comprising a box-form hollow body having its sides provided with passages and having one of its sides equipped with vertical guides, a plate movable in said guides and having a 20 passage therethrough, said plate being equipped with horizontal guides, and a second plate movable in said horizontal guides and provided with a flue-connection.
  3. A device of the character set forth comprising a rectangular box-form member having one side-wall provided with a passage and equipped with means for attachment to a wall and having its opposite wall provided with a passage, and a pipe-connection mounted on said last-named wall, said pipe 25 connection being adjustable both vertically and laterally.
  4. A flue device comprising a rectangular box-form member having its opposite sides provided with passages, vertical guides 30 at one of the sides of said member, a slide mounted in said guides and provided with an elongated horizontally disposed passage, and provided also with horizontal guides, and an elongated horizontal slide mounted 35 in said last-named guides and equipped with a pipe connection adapted to register with said last-named passage in various positions of said slides.

AUGUSTUS F. HARTER.
GEORGE D. WILKINSON.
